UNITED STATES PATENT OFFICE.

RUDOLPH F. PECINA AND ERIC V. CARLSON, OF LOS ANGELES, CALIFORNIA.

MUSICAL STRING-INSTRUMENT TUNER.

Application filed September 8, 1925. Serial No. 55,090.

Our invention relates to tuning devices for musical instruments, and more particularly to a tuning device for stringed musical instruments.

- 5 The general object of our invention is to provide a tuning device for stringed musical instruments, such as violins, which may be adjusted to hold the strings of the instrument in proper tension to produce tones of 60 the right pitch, and which will remain so adjusted when the strings break, and may be manipulated so that new strings may readily be connected thereto and held in proper tuning tension without further adjustment, 65
- 10 thus making it possible for anyone without a musical ear to substitute, for a broken string, a new one which will automatically be in tune.

Other objects and advantages will appear 20 hereinafter.

The invention is illustrated in the annexed drawing which forms a part of this specification and in which—

Figure 1 is a side view of a stringed musical instrument with our tuning device mounted thereon and holding the strings of the instrument in tuning tension.

Figure 2 is a plan view of the instrument and tuning device shown in Figure 1.

30 Figure 3 is a longitudinal section of the tuning device on an enlarged scale taken on line 3—3 of Figure 2.

Figure 4 is a plan view partly broken away, of the tuning device.

35 Figure 5 is a fragmentary side view of one of the tuning elements, shown in different positions.

Figure 6 is a plan view of one of the strings of the instrument constructed to be 40 connected to my tuner.

Corresponding reference characters designate the same parts in all the figures.

In the drawing A designates a musical instrument, such as a violin, comprising a 45 body 1, a neck 2, a tail piece 3, a bridge 4, strings 5, and finger board 6.

Our tuning device designated B is mounted on the upper end of the neck 2 of the instrument A and comprises generally a base plate 50 7, a hood 8, and a plurality of string tuning and holding elements 9 corresponding in number to the number of strings 5 of the instrument. The plate 7 is secured at its inner end in the upper end of the neck 2 of 55 the instrument A. The hood 8 fits over the

plate 7 and is detachably secured thereto near its lower edge by screws 10. Each string tuning and holding element 9 comprises a swingable arm 11, a hook 12, a spring 13, an arm engaging roller 14, and a push rod 15. The arms 11 extend through slots 16 in the plate 7 and are pivoted at their lower ends at 17 to a bracket 18 secured to the under side of said plate. The hooks 12 are formed with shanks 19 pivoted at one end at 20 to the arms 11. A cross bar 21 is screwed on the plate above and adjacent the upper end of the finger board 6 of the instrument A, which bar is formed with upturned flanges 22 and 23 along its upper and lower side edges and with a groove 24 between said flanges. The lower edge of the forward end wall of the hood 8 rests upon the upper edge of the upper flange 22 at 25. The flange 22 is provided with a plurality of notches 26 aligned respectively with the strings 5 through which notches extend the shanks 19 of the hooks 12, the hooks themselves normally resting within the groove 24. Each of the rollers 14 is journaled in 80 a pair of bearings 27 which are formed on the lower end of a spring 13 and straddle an arm 11. Each arm 11 is longitudinally grooved on its lower side as indicated at 28 to provide a trackway for a roller 14 to ride 85 in. In the upper end of each spring 13 is secured a nut 29 which receives a screw 30 extending through an opening 31 in a block 32 on the upper end of the plate 7, the head 33 of the screw engaging the upper side of 90 said block, said screw and nut through spring 13 drawing the roller 14 on the lower end of the spring against the lower side of an arm 11, whereby the hook 12 connected to said arm is drawn upwardly to tighten 95 and tune the string 5 which is connected to said hook. The opening 31 diverges downwardly so that the screw 30 may swing up or down from its head as a pivot against the block 32 to allow for the travel of the roller 14 up or down in the arm 11.

A lock nut 34 screws on each screw 30 against the nut 29 engaged by said screw, whereby the tension of the spring 13 held by said screw, is adjusted to hold a string 5 in proper tuning tension. Each push rod 15 is slidably mounted in a bearing 35 on the under side of the upper wall of the hood 8 in alignment with and in position for its lower end to engage the upper end of an arm 11, 110

the upper end of the rod extending out through the upper end wall of the hood, and a button 36 being secured on said end of the rod. A spring 37 normally holds each push 5 rod 15 withdrawn upwardly away from an arm 11, one end of said spring being connected at 38 to the bearing 35 and the other end of the spring being connected at 39 to the rod.

- 10 Each of the strings 5 of the instrument is formed with loops 40 and 41 at its lower and upper ends respectively. The lower loops of the strings engage lugs 42 respectively on the tail piece 3 of the instrument, 15 while the upper loops 41 engage the hooks 12 whereby the strings are held in position on the instrument.

When a string breaks the button 36 of the element 8 which holds the string, is pressed 20 downwardly, which correspondingly presses the rod 15 into engagement with the upper end of the arm 11 of said element and swings said arm downwardly against the tension of the spring 13 of said element, whereby the 25 hook of said element is pushed downwardly and is raised slightly by its engagement with the lower side of the groove 24 of bar 21 into position to be engaged by the upper loop 41 of a new string, the lower loop 40 of said 30 string having been first engaged with a lug 42 of the tail piece 3 of the instrument. The button 36 is then released, whereupon the spring 13 swings the arm 11 upwardly and draws the hook 12 and the string upwardly 35 until the string is drawn to the proper predetermined tension and tuned, the spring 13 holding said string being adjusted to hold the string in proper tuning tension, by means of the screw 30 and lock nut 34, thus 40 making it possible for one not having a musical ear to put a new string in the instrument in tuned tension.

A plurality of set screws 43 are seated in the block 32 and respectively engage the 45 screws 30 for preventing said screws, spring 13, and roller 14 from turning and disengaging the rollers from the arms 11.

We claim--

1. In combination with a stringed musical 50 instrument, a tuning device including means for engaging and holding the strings of the instrument in tuned tension, and a push rod independent of said engaging and holding means adapted for relaxing said engaging and holding means.

2. In combination with a stringed musical 55 instrument, a tuning device including means for engaging and holding the strings of the instrument in tuned tension, a slid able push rod independent of said engaging and holding means adapted for relaxing said engaging and holding means, and means for adjusting said engaging and holding means.

3. In combination with a stringed musical 60 instrument, a tuning device including a plu-

rality of string tuning elements corresponding in number to the number of strings of the instrument, each tuning element comprising a pivoted arm, a hook connected to said arm to which hook the upper end of one of the 70 strings of the instrument is connected, a spring, a roller journaled in one end of said spring and engaging said arm for drawing said arm, hook and string upwardly to tune the string. 75

4. In combination with a stringed musical instrument, a tuning device including a plurality of string tuning elements corresponding in number to the number of strings of the instrument, each tuning element comprising a pivoted arm, a hook connected to said arm to which hook the upper end of one of the strings of the instrument is connected, a spring, a roller journaled in one end of said spring and engaging said arm for drawing said arm, hook and string upwardly to tune the string, and means for adjusting the tension of said spring. 85

5. In combination with a stringed musical instrument, a tuning device including a plurality of string tuning elements corresponding in number to the number of strings of the instrument, each tuning element comprising a pivoted arm, a hook connected to said arm to which hook the upper end of one of the strings of the instrument is connected, a spring, a roller journaled in one end of said spring and engaging said arm for drawing said arm, hook and string upwardly to tune the string, and a push rod 90 for engaging said arm and swinging the same and drawing said hook downwardly for connecting the upper end of a string to said hook. 95

6. In combination with a stringed musical instrument, a tuning device including a plurality of string tuning elements corresponding in number to the number of strings of the instrument, each tuning element comprising a pivoted arm, a hook connected to said arm to which hook the upper end of one of the strings of the instrument is connected, a spring, a nut fixed in one end of said spring, a fixed block, a screw extending through said block and engaging said nut for adjusting the tension of said spring, a roller journaled on the other end of said spring and engaging said arm for drawing said arm, hook and string upwardly to tune the string. 105

7. In combination with a stringed musical instrument, a tuning device including a plurality of string tuning elements corresponding in number to the number of strings of the instrument, each tuning element comprising a pivoted arm, a hook connected to said arm to which hook the upper end of one of the strings of the instrument is connected, a spring, a roller journaled in one end of said spring and engaging said arm 110

for drawing said arm, hook and string upwardly to tune the string, a grooved member in which said hook normally rests and which said hook engages and is raised slightly thereby when the arm is swung and the hook moved downwardly for connecting a string to the hook.

8. In combination with a stringed musical instrument a tuning device including a plurality of string tuning elements corresponding in number to the number of strings of the instrument, each tuning element comprising a pivoted arm, a hook connected to said arm to which hook the upper end of one of the strings of the instrument is connected, a spring, a nut fixed in one end of said spring, a fixed block, a screw extending through said block and engaging said nut for adjusting the tension of said spring, a lock nut on said screw for locking the spring adjusted to the proper tension, a roller journaled on the other end of said spring and engaging said arm for drawing said

arm, hook and string upwardly to tune the string.

9. In combination with a stringed musical instrument, a tuning device including a plurality of string tuning elements corresponding in number to the number of strings of the instrument, each tuning element comprising a pivoted arm, a hook connected to said arm to which hook the upper end of one of the strings of the instrument is connected, a spring, a roller journaled in one end of said spring and engaging said arm for drawing said arm, hook and string upwardly to tune the string, a push rod for engaging said arm and swinging the same and drawing said hook downwardly for connecting the upper end of a string to said hook, and a lock nut on said screw for locking the spring adjusted to the proper tension.

In testimony whereof we hereunto affix our signatures.

RUDOLPH F. PECINA.
